Application November 25, 1932, Serial No. 644,251
 In Great Britain November 26, 1931

4 Claims. (Cl. 204—31)

The present invention relates to an electrode used in furnaces, in which a fluid having a great dielectric strength, such as liquid hydrocarbon, is submitted to a fixed or rotary arc, or to disruptive discharges. This electrode is opposite to, and at a little distance from, a hollow electrode, having substantially the same axis and through the interior of which the fluid to be treated is supplied to the arc. In proportion of their wear, 5 the electrodes are fed one to the other in order to maintain the small suitable length of the arc, bound to the dielectric strength of the fluid to be treated.

When the electrode, of which the present invention is an improvement, is solid, it is worn in such a manner that a larger and larger projection is progressively formed in its central part, owing to the more rapid wear of the adjacent peripheral parts, which are opposite to the solid 10 active part of the hollow electrode. Therefore, when the two electrodes are fed together to maintain the arc at the small desired length, this projecting part, even if small, engages in the fluid supply conduit of the hollow electrode and may 15 provoke short-circuits, if it comes into contact with this hollow electrode, the wear of which is therefore made irregular.

The present invention has particularly for its object to remedy these drawbacks; it consists in 20 using, as an electrode situated substantially opposite to the hollow electrode, an electrode (that will be also thereafter called counter-electrode) that is provided with a central cavity extending from its active end for a part of its length towards 25 its closed end and in which the sections perpendicular to its axis, along its hollow part, made at different distances from its active end are identical to the sections of the opposite electrode, perpendicular to its axis, made at the same 30 distances from the active end of said electrode.

This counter-electrode is constituted, for example, by a cylindrical rod of carbon bored for a certain part of its length or even by a cylindrical tube one of the extremities of which is provided 35 with a cap, so as to close the interior cavity of this tube.

Preferably the counter-electrode terminates in a flat face perpendicular to its axis and the hollow electrode terminates also in a flat face perpendicular to its axis.

The counter-electrode and the hollow electrode 40 constitute a set of electrodes in which the active surfaces from which the arc jumps at the extremity of each electrode are, at each moment of the 45 working of the furnace, equal and parallel to-

gether and perpendicular to the axis of the electrodes. The arc jumps therefore in a uniform manner between the two electrodes and these are equally worn away. Consequently, in spite of the wear of the electrodes, their active surfaces 50 remain substantially parallel and the steadiness of the arc is obtained. This parallelism of the active surfaces of the electrodes affords a particularly important advantage in the case where 55 liquid hydrocarbons are treated by the arc, for the length of the arc is only a few millimetres.

An embodiment of the invention is diagrammatically illustrated, by way of an example, in the accompanying drawing.

In this drawing A denotes a cylindrical tubular 70 rod through the interior of which the liquid to be treated is supplied to the arc which jumps between this electrode A and an opposite electrode B. This electrode B is a cylindrical rod, coaxial with the electrode A and having the same 75 diameter; it is provided with a cylindrical cavity C, which extends only for a part of its length from its active end and the diameter of this cavity is equal to the inner diameter of the tubular electrode A. The electrodes A and B terminate 80 in a flat annular face, which is perpendicular to their common axis, and constitutes the active part of these electrodes.

Instead of using the counter-electrode in its hollow form, its cavity may be filled, before the 85 electrode being used, by a suitable substance, able to be progressively brought away under the influence of the heat of the arc (or of the current of fluid supplied through the hollow opposite electrode) simultaneously with the wear of the 90 active part of this counter-electrode: for example, use may be made of pitch for this purpose.

When liquid hydrocarbons are to be treated by the arc, it is not necessary to previously fill the cavity of the counter-electrode: this cavity 95 becomes automatically filled, after the arc is struck, with a pasty mass constituted by a mixture of the liquid hydrocarbon submitted to the treatment by the arc and of the carbon formed by the decomposition of this hydrocarbon; this 100 pasty mass is also worn away progressively at the same time as the active part of the counter-electrode is worn.

Although the wear of the electrodes generally 105 takes place regularly over their whole active face, it is possible, with a view to make such wear more uniform, to impart to one of the electrodes (or to both electrodes) an axial rotary movement, the current supply being effected by suitable contact brushes and rings. Further the electrodes 110

may be fixed and the arc could be submitted to the action of a magnetic field such as would impart to the arc a rotary movement around the axis of the electrodes.

5 What I claim is—

1. In a set of electrodes for furnaces in which a fluid having a great dielectric strength is submitted to an electric treatment, a hollow electrode through the interior of which the said fluid is supplied to the arc, a counter-electrode situated substantially opposite to the first electrode and at a small distance from said electrode, a central cavity in said counter-electrode extending from its active end along a substantially long part of said counter-electrode, a solid part at the rear end of said electrode closing the said cavity, the sections of the said counter-electrode, perpendicular to its axis, made at different distances from its active end along its hollow part being identical to the sections of the opposite electrode, perpendicular to its axis, made at the same distances from the active end of said electrode.

2. In a set of electrodes for furnaces in which a fluid having a great dielectric strength is submitted to an electric treatment, a cylindrical electrode, a central cylindrical channel extending along the entire length of said electrode and through which the said fluid is supplied to the arc, a cylindrical counter-electrode situated at a small distance from the first electrode and with its axis in alignment with the axis of said electrode, said counter-electrode having the same transversal shape as the opposite electrode, a central cylindrical cavity in said counter-electrode extending from its active end along a substantially long part of said counter-electrode, a substance capable of being worn away in proportion to the wear of said counter-electrode filling the said central cavity, a solid part at the rear end of said electrode closing the said cavity, the sections of the said counter-electrode, perpendicular to its axis, made at different distances from its active end along its hollow part being identical to the sections of the opposite electrode, perpendicular to its axis, made at the same distances from the active end of said electrode.

3. In a set of electrodes for furnaces in which

a fluid having a great dielectric strength is submitted to an electric treatment, a cylindrical electrode, a central cylindrical channel extending along the entire length of said electrode and through which the said fluid is supplied to the arc, said cylindrical electrode terminating in a flat face perpendicular to its axis, a cylindrical counter-electrode situated at a small distance from the first electrode and with its axis in alignment with the axis of said electrode, said counter-electrode having the same transversal shape as the opposite electrode, and terminating in a flat face parallel to the end face of the first electrode, a central cylindrical cavity in said counter-electrode extending from its active end along a substantially long part of said counter-electrode, said cavity having the same transversal shape as the channel in the first electrode, and a solid part at the rear end of said counter-electrode closing said cavity.

4. In a set of electrodes for furnaces in which a fluid having a great dielectric strength is submitted to an electric treatment, a hollow electrode through the interior of which the said fluid is supplied to the arc, a counter-electrode situated substantially opposite to the first electrode and at a small distance from said electrode, a central cavity in said counter-electrode extending from its active end along a substantially long part of said counter-electrode, a substance capable of being worn away in proportion to the wear of said counter-electrode filling the said central cavity, a solid part at the rear end of said electrode closing the said cavity, the sections of the said counter-electrode, perpendicular to its axis, made at different distances from its active end along its hollow part being identical to the sections of the opposite electrode, perpendicular to its axis, made at the same distances from the active end of said electrode.
